M. J. WOHL,
MULTIPLE ARC LAMP.
APPLICATION FILED APR. 18, 1916.

Patented July 31, 1917.
2 SHEETS—SHEET 2.

UNITED STATES PATENT OFFICE.

MAURICE J. WOHL, OF BROOKLYN, NEW YORK, ASSIGNOR TO M. J. WOHL AND COMPANY, OF BROOKLYN, NEW YORK, A COPARTNERSHIP COMPOSED OF MAURICE J. WOHL AND MAX MAYER.

MULTIPLE-ARC LAMP.

1,235,271.

Specification of Letters Patent.

Patented July 31, 1917.

Application filed April 18, 1916. Serial No. 91,867.

To all whom it may concern:

Be it known that MAURICE J. WOHL, a citizen of the United States, and resident of Brooklyn, city of New York, county of 5 Kings, and State of New York, has invented certain new and useful Improvements in Multiple-Arc Lamps, of which the following is a specification.

This invention relates to electric arc 10 lamps and more especially to multiple arc lamps and it has for an object to provide an improved construction whereby a more uniform relative feed and adjustment of the different carbons may be effected and which 15 will act to eliminate noises in the lamp. A further object is to provide means for preventing the current in one arc from influencing the current in another arc.

These and other objects and details of 20 the invention will be more fully described in the following specification, set forth in the appended claims and illustrated in the accompanying drawings forming a part of this application and wherein;

25 Figure 1 is a sectional view through the box inclosing the lamps showing them from the front.

Fig. 2 is a transverse vertical sectional view through one end of the box.

30 Fig. 3 is a detail view of the buffer for the feed means.

The lamp arrangement shown in the drawings is especially adapted for use where a constant light is necessary and 35 where the operation of the feed should be noiseless. To produce this result the device is mounted in a box 5 of the desired size and divided horizontally by the partition 6, the lower compartment 7 containing the 40 lamps 8, 9, 10 and 11 and being painted or coated with a reflecting material to throw the light of the lamps out of the opening 12.

The upper compartment 13 contains the 45 solenoids 14, dash pots 15 and spring connections of the clutches 16, also guide rods 17 on which play the cross bars 18 carrying the sockets 19 for the upper carbons 20. The lower carbons 21 are stationary and are suspended in frames 22 by means of rods 23 50 from a platform 24 hung from the partition 6 by means of bolts 25. The rod 23 also carries a magnetic shield 26 to shield each arc from the magnetic effects of the current in the adjacent arc in a set and to prevent the 55 irregular wearing of the carbons at their ad-

jacent points. The shield 26 is of thin metal and almost completely partitions the compartment 7, effectually separating the different arcs but not interfering with the escape of light through the openings 12. 60

Each solenoid 14 is secured to the inner top wall of the upper compartment 13 by means of rods 28 which also carry at their lower ends dash pots 16. From the core of the solenoid extends a rod 29 carrying at 65 its lower end the plunger 30 operating in the dash pot 15 and interposed between the plunger and the rod 29 are the vertically spaced horizontal springs 31 joined at their outer ends by bolts 32, and fixed upon the 70 lower springs is a cross bar 33, the ends of which carry the rods which connect the cross bar with the clutches 16 to operate the upper carbon at the proper time. These rods are here shown as composed of separate 75 upper and lower members 35 and 36 joined together by the angular springs 34 which are secured at opposite ends to the respective members 35 and 36. With the above described arrangement of springs a resilient connection is effected between the solenoid core and the dash pot and further resilient connections between the dash pot and clutches. To prevent injury to the springs 80 34 from too great compression during insertion of a carbon in place I have shown the adjacent ends of the members 35 and 36 as projecting into the space between the springs 34 so as to limit the compressional movement of the springs by engagement with one 85 another, the lower member having an upturned fork 37 in which is received the end of the upper member. 90

By the arrangement of a single solenoid to control a plurality of arcs I am enabled 95 to insure of a more even consumption of the carbons and a more even light from each arc since the lifting force transmitted to each carbon will be the same, which result can not be secured with any degree of accuracy 100 by individual solenoids and dash pots for each arc.

The circuit connections are down one lamp and up the companion lamp, the upper carbon of one set of lamps being the negative pole of the current while the adjacent upper carbon is positive, the course of the current being downward and then upward, or vice versa. 105

The use of one solenoid for each pair of 110

2

lamps also simplifies the construction of the lamp while the resilient connections take up the vibration in the solenoid core when alternating current is used and prevent noise 5 the whole arrangement resulting in a simple and silent device. It is obvious that the parts may be otherwise arranged or modified without departing from the essential features above described or from the scope 10 of the appended claims.

As will be noted, the construction described provides a resilient connection between the solenoid core and the dash pot and a further resilient connection between 15 the dash pot and carbons, which arrangement has been shown in actual practice to be extremely efficient in eliminating flickering of the light due to vibration of the carbons.

20 What I claim as new is:

1. In a multiple arc lamp, two carbon pairs, a clutch for each pair, longitudinally resilient vertical rods connected one to each clutch at their lower ends, a resilient yoke 25 uniting the upper ends of the rods, and a solenoid having its core connected to said yoke midway between the ends of the latter.

2. In a multiple arc lamp, two carbon pairs, a clutch for each pair, longitudinally 30 resilient vertical rods connected one to each clutch at their lower ends, a resilient yoke consisting of a pair of horizontally arranged and vertically spaced flat springs connected together at their ends and a bar

supported on the lower spring, said bar 35 having the upper ends of the resilient rods connected to its ends, a solenoid having its core connected to the upper spring midway between the ends of the latter and a dash pot connected to the lower spring midway 40 between the ends of the latter.

3. In an arc lamp, in combination, a solenoid, a pair of carbons a clutch therefor, and a longitudinally resilient rod forming a connection between the said clutch and the core 45 of the solenoid, said rod comprising upper and lower members and a pair of springs bent outwardly between their ends connecting said upper and lower members, one of said members presenting at the end adjacent 50 the other rod member a recess adapted to receive the last mentioned member, for the purpose set forth.

4. In an arc lamp, in combination, a solenoid, a pair of carbons, a clutch therefor, 55 and a longitudinally resilient rod forming a connection between the said clutch and the core of the solenoid, said rod comprising upper and lower members and a pair of springs bent outwardly between their ends 60 connecting said upper and lower members, one of said rod members presenting at the end adjacent the other rod member a fork into which the end of the last mentioned rod member projects.

Signed at city, county and State of New York, this 27th day of March, 1916.

MAURICE J. WOHL.
